UNITED STATES PATENT OFFICE.

JULIUS LUTZ, OF HEIDELBERG, GERMANY.

PRINTING PROCESS.

1,201,599.

Specification of Letters Patent. Patented Oct. 17, 1916.

Application filed May 18, 1915. Serial No. 28,897.

To all whom it may concern:

Be it known that I, JULIUS LUTZ, a subject of the Grand Duke of Hesse, German Empire, residing at the city of Heidelberg, in the Grand Duchy of Baden, Germany, have invented certain new and useful Improvements in Printing Processes, of which the following is a specification.

My invention relates to a printing process similar to lithography, that is to say, being based on the principle that the wetted background of the printing plate repulses the ink and the printing ink, repulsing the water, takes up the ink.

15 It is known that prints may be produced from zinc and aluminium plates, by the picture of the writing being applied by aid of transfer paper to the prepared plate and the said plate thereupon being drawn around

20 a cylinder. The printing is performed in the known manner by wetting the printing surface and subsequently rolling the ink onto it, and finally receiving the impression on paper on the counter-cylinder.

25 With this process the printing surface must be wetted from outside, which has the great disadvantage, that the writing or the picture appears dull and indistinct at a comparatively small output, because the liquid

30 will, in wetting the surface, impair the transfer of the ink and a deep black can only be secured at a slow revolution. The offset-process, by which the printing is first transferred from the zinc or aluminium cylinder to a rubber cylinder, therefore also allows of a slow speed only, as, also here, the printing surface has to be wetted.

35 The novel feature of my invention consists therein that the printing is made directly from the original, which has been printed on a suitable, flexible material. Furthermore this material may be wetted from the back, so that when a cylinder printing machine is employed, the wetting of the surface at each printing operation is dispensed with.

40 The present invention consists in the process of placing a flexible material, (which will absorb water and on which the writing or picture to be reproduced is printed in the usual manner), on a printing cylinder and printing from the same after the lithographic printing system, that is to say, after wetting the said material and subsequently inking it.

45 When a rotary cylinder printing machine

is employed the wetting is effected from the inside of the cylinder on which the material carrying the original print, and serving as printing surface, is placed. When the 50 whole surface of this material has been wetted, the wetted part will, at the subsequent inking with the ink roller, not take up the ink, but the writing or drawing printed onto the material will take up the 55 ink and transfer it, at the subsequent printing operation, to the paper.

The operation according to my new process is as follows:

The machine employed is shown in diagram 70 in Figure 1. Fig. 2 is a section through the cylinder adapted for wetting the material from inside.

In Fig. 1 A is the printing cylinder on which is mounted the flexible, porous sheet 75 containing the original matter to be printed. This original is a printed impression in a fatty or water-repellant ink, say, for example, a piece of paper that has previously been printed in the ordinary way; the essential being that it should be porous so as to absorb water. Ink is supplied from any suitable ink font F to a distributing and inking roller train D of well known type and to the wetted paper on the printing 80 cylinder A:

The ink adheres to the previously printed or inked portions on the printed porous paper originally on cylinder A and is repelled by the wet unprinted portions, so 90 that the lines take the ink from the printing train. The original being a positive, the inked design of this positive is transferred as a reversed (sometimes called a negative) design to a rubber or equivalent transfer 95 roller in the manner of an offset. This transfer roller then transfers the design as a positive to the paper web W on the impression cylinder C.

The paper is contained in a roll P, and 100 the web W is guided from this roll over guide rolls G around the impression cylinder C, over guide roll E and between drawing rolls H.

The construction of press just described 105 is that common to many forms of web printing presses, and no further description is deemed necessary.

On a soft material which will take up a printing and is permeable to water or 110 endosmotic, such as paper, parchment, prepared linen, shirting or the like material.

having the said properties the design to be reproduced is printed by means of an ordinary printing press. This material thus printed serves, as hereinafter described, as 5 print transerrer. In a machine having three cylinders the first cylinder A serves to receive the printed material, (original), which is, however, not applied to the cylinder directly, but to a jacket of felt or the 10 like on the cylinder. This jacket is intended to receive and store the water for wetting and to transmit the same to the original from the inside during the printing operation. For this purpose the cylinder A is 15 so constructed, that it can receive the water, having its ends flanged as shown at *a*, which are bent over toward the axis and allow of the water entering the interior thereof (see Fig. 2). The inner mantle *b*, on which the 20 jacket *c* is fitted, is provided with fine perforations *d*, through which the water will pass during the printing operation. For small editions the jacket may, also, be made of such thickness, that one wetting of 25 the same will suffice, such wetting, in this case, being made before the printing is commenced. In the same manner the original may, according to its own thickness, print a small edition with one single wetting or 30 rewetting. It is, however, not intended to claim, that the wetting of the surface of the original is not admissible; such outward wetting may also, also be employed, only in this case the impressions will not be as good. 35 When the drawings, designs or the like are of such a character, that the impression may also be a negative, it is possible to make the impressions directly from the original. With letter press or writing, however, which 40 are produced as positives by the printing press, it is necessary to employ a transfer cylinder in order to avoid receiving a negative impression. This transfer is obtained, the same as with the offset-machine, by 45 means of a second cylinder B, which is covered with india rubber cloth and will, in known manner, transfer a positive impression to the paper. The third cylinder C is the counter-cylinder which is employed for 50 pressing the paper tightly against the india rubber cylinder and for allowing of the im-

pression being taken off. The inking is performed in the same manner as with the stereotype rotary printing machine. The inking rollers are pressed against the printing cylinder A and there ink the design, while the other parts of the original do not take up any ink. 55

I claim:

1. A printing process comprising wetting 60 an already printed sheet of customary material having the usual printed surface that has been printed in a water-repellant ink, and directly inking said already printed wetted sheet and printing therefrom. 65

2. A printing process comprising wetting 70 an already printed sheet of paper as ordinarily used in printing presses and printed in the customary manner with the customary water-repellant ink, inking the wetted print and printing therefrom. 75

3. A process comprising wetting a customary print on paper customarily used in printing presses, maintaining the paper wet from the back thereof, inking the print, 80 and printing from the inked print. 85

4. A printing process consisting in wetting 90 a sheet of fabric, paper and the like, customarily used for making impressions in printing presses, but not specially prepared as impression or printing surface, and having a printed impression thereon in the customary water-repelling printing ink, inking such wetted printed surface and printing therefrom. 95

5. In a printing process in which a sheet of fabric, paper and the like customarily used for making printing press impressions but not specially prepared as a printing or impression surface and having a printed impression thereon, the improvement which consists in wetting such already printed sheet from the back, inking the wetted sheet and printing therefrom, either directly or by offset. 95

In testimony whereof I have affixed my signature in presence of two witnesses.

JULIUS LUTZ.

Witnesses:

C. INNESS BROWN,
Frau KINZER.
